UNITED STATES PATENT OFFICE.

HEINRICH STIELER, OF FRANKFORT-ON-THE-MAIN, GERMANY.

FIRE-LIGHTING DEVICE.

Application filed March 23, 1926, Serial No. 96,829, and in Germany March 23, 1925.

Fire lighters consisting of waste material from the timber industry, or peat soaked or mixed with resins or tar or like readily combustible substances all have the disadvantage, that they develop large quantities of soot when burning on the grate. More particularly in the case of large industrial furnaces, when firing up locomotives and the like, where fire lighters of considerable size are required, the formation of soot is found to be exceedingly detrimental, as the soot adheres for instance to the smoke tubes and adversely affects the full utilization of the heat. A further disadvantage is, that with such fire lighters, coal can only be lighted slowly, while it is difficult to light coke and anthracite at all with such fire lighters, if they are simply laid on the grate under the coal in the usual manner and lighted.

The inventor has succeeded in overcoming these drawbacks, by not introducing the fire lighters, as has been done heretofore, simply into the furnace space and lighting them there, but by burning them by means of a special device, in which a sufficient quantity of air is supplied to the fire lighter in such a manner that the formation of soot is prevented and complete combustion takes place. The new apparatus is preferably made so as to be portable and of such a shape as to be easily introduced through the fire door into the fire space. The formation of soot may be prevented, for instance by air being blown, for instance through nozzles, against the front surface of the fire lighter which is placed in a sort of combustion chamber, such that the smoke produced during combustion is forced back into the combustion chamber and is caused to be completely burned. Provision may also be made, for instance by completely enveloping the fire lighter with air or by repeatedly introducing air at points in the combustion chamber, lying one behind the other, or at the outlet of the same, for completely burning the flakes of soot. The fine flame produced in the manner referred to suffices for igniting any kind of coal.

The air may be supplied for instance through a movable pipe, for instance connected pivotally to the combustion chamber, or through flexible metal tubing, which enables the combustion chamber to be placed at any suitable point of the grate. The stream of air may for instance be taken from an air compressor or a compressed air bottle or be

delivered by a small device acting in the manner of a blower, which is connected to the air supply pipe or to the apparatus itself and may for instance be driven electrically. In place of air oxygen or a mixture of atmospheric air and oxygen may be used.

In the accompanying drawings one of the many possible constructional examples of the invention is shown.

Fig. 1 shows a modified form of the combustion chamber of a tubular apparatus in section,

Fig. 2 shows the same apparatus with the damper open after the fire lighter has been burned, and

Fig. 3 shows the whole apparatus illustrated in Figs. 1 and 2.

In the arrangement shown in the annexed drawings a grate 24 is provided in the chamber 23, on which the lighter 25 is placed through the front opening in the chamber, the grate 24 being pressed down, the hook 26 forced back and the damper 27 being pushed into the position shown in Fig. 1. With the parts in this position the projection or cam 28 on the extension 29 of the grate which is pivoted at 30 rests against the lower end of the damper 27.

The combustion air is produced for instance by the fan 31 which may be connected directly to the apparatus by the pipes 32 and 33. The pipe 33 may be connected at 34 to the apparatus by means of a cylindrical or conical joint. The air entering the forward part 35 of the chamber lying behind the damper passes through the openings 36 into the space between the outer casing 37 and the casing 38 of the combustion chamber and flows out through the annular nozzles 39 and 40. Nozzle apertures 41 may also be provided in the front part of the combustion chamber, from which the air will enter the interior of the combustion chamber, for instance in the form of a screen, which places itself in front of the fire lighter.

When the fire lighter has burned away, the grate 24 will no longer be loaded and will rise under the action of the counterpoise 42. The damper will be released by this means, so as to be free to turn under the pressure of the stream of air into the position shown in Fig. 2. The air is now free to pass through the combustion chamber and, after the rest of the fire lighter has been consumed, acts as an additional stream of air

for assisting the coal which has been lighted to be set burning thoroughly.

The outer casing in the example just described is made in the shape of a roof, for 5 protecting the combustion chamber, when coal is thrown on the fire while the lighter is in action. This form of outer casing also facilitates the withdrawal of the apparatus from the heap of coal. In the tunnel formed 10 in this manner the jet-shaped flame or the air from the fan can be particularly effective.

The constructional forms described are only given by way of example and many modifications are possible without departing 15 from the spirit of the invention, for instance by changing the shape of the casing, the arrangement of the nozzles, modifications of the movable and additional parts, such as the grate, the damper, the outer casing, the 20 means for producing the air supply and the like.

What I claim is:

1. A device for lighting fires, including a 25 casing for the reception of a fire lighter, and means for supplying compressed air to said casing during burning of a fire lighter in such quantity and so distributed as to effect complete combustion of smoke, a damper controlling passage of air through the air 30 supply means, means for retaining said damper in closed position, and means actuated during the progress of the consumption of fire lighter for releasing and permitting said damper to open.

2. A device for lighting fires, including a 35 casing for the reception of a fire lighter, and means for supplying compressed air to said casing during burning of a fire lighter in such quantity and so distributed as to effect complete combustion of smoke, and an outer 40 casing receiving the first mentioned casing and adapted to receive air.

3. A device for lighting fires, including a 45 casing for the reception of a fire lighter, and means for supplying compressed air to said casing during burning of a fire lighter in such quantity and so distributed as to effect complete combustion of smoke, and an outer casing receiving the first mentioned casing 50 and adapted to receive air, said outer casing being connected with the air supply means.

4. A device for lighting fires, including a 55 casing for the reception of a fire lighter, and means for supplying compressed air to said casing during burning of a fire lighter in such quantity and so distributed as to effect complete combustion of smoke, a damper in 60 said air supply means, a counter balanced grate in said receptacle for supporting a fire lighter, and means on said grate for releasably holding said damper in closed position.

5. A device for lighting fires by combustion of fire lighters with compressed air comprising a main air conduit, a ball joint on 65 said conduit, an air conducting tube attached to said ball joint, a casing attached to said tube, a box for the reception of the fire kindler connected to said air tube and arranged in said casing in such a manner that there is a space between the walls of said box 70 and those of said casing, means to lead air from said tube into the space between said box and said casing and means to bring air into contact with the products of combustion leaving said box. 75

6. A device for lighting fires by combustion of fire lighters with compressed air comprising a main air conduit, a fan in said conduit, a ball joint on said conduit, an air conducting tube attached to said ball joint, 80 a casing attached to said tube, a box for the reception of the fire kindler connected to said air tube and arranged in said casing in such a manner that there is a space between the walls of said box and those of said casing 85 and means to bring air into contact with the products of combustion leaving said box.

7. A device for lighting fires by combustion of fire lighters with compressed air comprising an air conducting tube, a casing attached to said tube, a box for the reception of the fire kindler connected to said air tube and arranged in said casing in such a manner that there is a space between the walls of said casing and said box, a damper in said 90 box in front of the exit of said air tube, openings in the walls of said box between said damper and said tube, a movable grate in said box, means to control said damper by said movable grate and means to bring air 100 into contact with the products of combustion leaving said box.

8. A device for lighting fires by combustion of fire lighters with compressed air comprising an air conducting tube, a box for the 105 reception of the fire kindler connected to said tube, a damper in said box, a grate pivotally arranged in said box, an extension on said grate, a weight on said extension, a projection on said extension engaging through 110 the box with said damper, openings in the walls of said box between said air tube and said damper, a roof-like casing attached to said air tube and surrounding the box in such a manner that there is a space between 115 box and casing and means to bring fresh air into contact with the products of combustion leaving said box.

In testimony whereof I have signed my name to this specification.

HEINRICH STIELER.
